UNITED STATES PATENT OFFICE

2,661,514

PIVOTED LOCKING MEANS FOR LINES

Victor Martin, Parkstone, England; Amelia Ada Martin and Doris Attwell, administratrices of said Victor Martin, deceased

Application April 11, 1951, Serial No. 220,467

Claims priority, application Great Britain May 26, 1950

2 Claims. (Cl. 24—134)

1

The present invention relates to an improved line lock for a cable, cord or line, for example, a line used in a kitchen for domestic purposes.

An object is to produce a simple and efficient line lock which is simple in construction, easy to assemble, has great mechanical advantage, and includes the novel features of construction, arrangement and operation hereinafter described.

A preferred form of the invention will now be described with reference to the diagrammatic drawings in which:

Figure 1 is an elevation of the locking means, Figure 2 is a side elevation thereof,

Figure 3 is an elevation of the same locking means but with the cover plate removed,

Figures 4, 5 and 6 are respectively a plan, side and end elevation of a lever, also shown in the other figures,

Figure 7 is a front elevation of a line lock,

Figures 8 and 9 are end elevations respectively of a base plate shown in Figure 7 and

Figure 10 is a sectional elevation of a wall plate also shown in Figure 7.

The line lock illustrated in Figures 1 to 6 (provisional specification) comprises a rectangular base plate 10 formed at its top and bottom with apertured lugs 11 and 12 respectively, with the aid of which the device may be secured, in the position shown on the figures, to a wall or the like.

At its left hand side the base plate is cut away as at 13 and 14 to leave room for the line L which is to be locked. The base plate is also formed with a V-shaped cutaway 15, 16 running into a notch 17 and a parallel sided channel 18.

Fixed on the base plate is a pivot 19 for a two-armed lever 20 of unequal arms, details of which are shown in Figures 4, 5 and 6. It will be seen from these figures that the leading or longer end of the lever is recessed as at 21 to prevent the line L from slipping out of engagement with this end.

For the same purpose the outer end of the channel 18 is formed with a recess 22 to hold the loose end of the line L.

The base plate is provided with a cover plate 23 which can be secured by a nut 24 screwing onto the pivot 19.

As can be seen from Figure 2 the thickness of the lever 20 is slightly less than the depth of the cut away portion of the base plate so that the lever 20 is free to pivot between the cover plate and the base plate.

In operation the base plate is screwed to a wall and the line L to be locked is fitted under the

2

lever 20 and into the channel 18 so as to engage the recesses 21 and 22.

The load on the line L acting in an upward direction is effective to rotate the longer end of the lever 20 in clockwise direction so that the shorter end grips the line at the points A—B with mechanical advantage and locks it at this position, the point B constituting an abutment for the line.

It will be noticed that the strength of the locking action is proportional to the load on the line and to the difference in length of the two arms of the lever so that the greater the load the tighter is the line locked.

15 The line is released by taking off the load and then slipping the line sideways out of the device.

The line may be inserted and removed whether or not the cover plate is in position.

The notch 17 serves as a stop limiting the travel of the lever in anticlockwise direction.

The embodiment illustrated in Figures 7 to 10 comprises a wall plate indicated generally at 30 in the form of an annulus formed with a circular rebate 31. It is also formed with three screw holes 32, 33 and 34 and with a radial bore 35.

Fitting within the wall plate 30 is a disc-like base plate, indicated generally at 36, formed with a rebate 31, co-operating with the rebate 31 of the wall plate, and with a boss 38.

30 The base plate 36 can be fitted into the annulus and, when the latter is screwed to a wall or the like, the base plate is rotatable in the wall plate. In order that the base plate may be locked in a predetermined angular position within the wall plate a pin 39 is provided which can be inserted through the bore 35 in the wall plate into a recess 40 formed in the base plate.

As in the case of the last embodiment the boss 38 is formed with a V-shaped cutaway 41, 42 running into a notch 43 and a parallel sided channel 44.

45 At its centre the boss 38 carries a pivot 45 on which is a lever 46 similar in all respects to that illustrated in Figures 1—6. As before, the outer end 47 of the channel 44 is recessed or grooved as at 48 (Figure 9) to prevent the line from slipping out of engagement with this end. The leading end of the lever is similarly grooved.

The base plate is locked in its operative position on the wall plate by insertion of the pin 39 into the bores 35 and 40 and then functions in exactly the same way as the last described embodiment.

50 A cover plate 49 may be screwed onto the end 55 of the pivot pin 45 if desired, although the de-

vice functions quite well without a cover plate. A light return spring may be used to hold the lever away from the abutment 42.

In order to release the line, however, all that is necessary is to withdraw the pin 39.

Either of these devices may be used in any situation where it is desired to lock and free the line alternately.

I claim:

1. A locking means for a line, comprising a wall plate adapted to be affixed on a wall or the like support, a base plate rotatably mounted on said wall plate whereby said base plate may be angularly adjusted clockwise and counterclockwise with respect to said wall plate, said base plate having an open-sided channel extending therethrough between generally opposite portions of the periphery thereof for receiving a line, the base plate along one side of said channel constituting an abutment, a simple lever having arms of unequal length pivoted to said base plate in said channel for swinging about an axis normal to the plane of the base plate at a point spaced from said abutment for engaging the line against said abutment, the shorter of the lever arms swinging against said line and towards said abutment in response to pull of said line against the longer of the lever arms, and releasable locking means engaging between said plates for maintaining said base plate in angularly adjustable position, whereby said base plate may be adjusted to and maintained in an angular position selected in accordance with the lead of the line.

2. A locking means for a line, comprising an annular wall plate adapted to be affixed on a wall or the like support, a disc-shaped base plate rotatably engaged in said annular wall plate where-

by said base plate may be angularly adjusted clockwise and counter-clockwise with respect to said wall plate, said base plate having an open-sided channel extending therethrough between generally opposite portions of the periphery thereof for receiving a line, the base plate along one side of said channel constituting an abutment, a simple lever having arms of unequal length pivoted to said base plate in said channel at a point spaced from said abutment for engaging the line against said abutment, the shorter of the lever arms swinging against said line and towards said abutment in response to pull of said line against the longer of the lever arms, and releasable pin means engaging through the periphery of said wall plates for maintaining said base plate in angularly adjustable position, whereby said base plate may be adjusted to and maintained in an angular position selected in accordance with the lead of the line.

VICTOR MARTIN.
